GAUGE

Walter Pszegon, Woodlyn, Pa.

Application November 6, 1952, Serial No. 319,115

1 Claim. (Cl. 33—197)

This invention relates in general to carpenter's tools, and more specifically to a gauge for setting hinges of a door.

The primary object of this invention is to provide an improved gauge set which may be utilized in the hanging of doors, said gauge set being adapted to be placed on a door jamb and an edge of a door for outlining that portion of the door jamb and door which must be cut-away for the proper positioning of leaves of hinges.

Another object of this invention is to provide an improved gauge set for aligning hinge leaves of hinges and hanging of doors, said gauges being of a relatively simple construction and capable of being accurately set for outlining those areas that must be cut away for the reception of leaves of door hinges.

A further object of this invention is to provide an improved door hinge gauge set which includes a pair of co-operating hinge gauges, said hinge gauges being adapted to be readily set in place on a door jamb and an edge of a door outlining an area which must be cut-away from the reception of a hinge leaf.

A still further object of this invention is to provide an improved scriber which has a blade adapted especially for the outlining of an area to be cut-away for the reception of a hinge, said scriber having a blade adapted to cooperate with a door hinge gauge so as to penetrate a portion of a door jamb or door a desired depth, said depth being equal to the thickness of a hinge leaf adapted to be inserted into the door jamb or door.

These together with other objects and advantages which will become subsequently apparent reside in the details of construction and operation as more fully hereinafter described and claimed, reference being had to the accompanying drawings forming a part hereof, wherein like numerals refer to like parts throughout, and in which

Figure 1 is a fragmentary perspective view of an edge on a door adapted to be hung, said door having mounted thereon a door gauge especially designed for marking the area of the door to be cut-away for the reception of a hinge leaf;

Figure 2 is a fragmentary side elevational view of the door of Figure 1 and shows the outline of an opposite side of the door gauge;

Figure 3 is an enlarged fragmentary sectional view taken substantially upon the plane indicated by the section line 3—3 of Figure 1 and shows the arrangement of an adjustable plate carried by the door gauge for facilitating the clamping of the door onto an edge of the door;

Figure 4 is a vertical sectional view taken substantially upon the plane indicated by the section line 4—4 of Figure 3 and shows the general configuration of the plate for clamping the door;

Figure 5 is a fragmentary perspective view of a portion of a complementary door jamb, said door jamb having secured thereto a jamb gauge for outlining a portion of the same adapted to be cut-away to receive a hinge leaf;

Figure 6 is an enlarged fragmentary vertical sectional view taken substantially upon the plane indicated by the

2

section line 6—6 of Figure 5 and shows the general cross-section of the central portion of the jamb gauge and the manner in which the same is secured to a door jamb;

Figure 7 is a fragmentary transverse horizontal sectional view taken substantially upon the plane indicated by the section line 7—7 of Figure 6 and shows the manner in which a scriber may be utilized in combination with the jamb gauge for outlining an area to be cut-away for the reception of a door hinge leaf; and

Figure 8 is an elevational view of the bottom portion of the scriber illustrated in Figure 7 and shows the configuration of the blade portion thereof.

Similar characters of reference designate similar or identical elements and portions throughout the specification and throughout the different views of the drawings.

Referring now to Figures 1 to 4, inclusive, in particular, it is seen that there is illustrated a door gauge, which is referred to in general by the reference numeral 10, for mounting on a door to facilitate the outlining of an area of the door which must be cut-away for the reception of a hinge leaf. The door gauge 10 is illustrated as being mounted on an edge portion of a door 12 and is in position for the scribing of lines on one edge and a portion of one face of the door 12 to facilitate the removal of a portion of the door for reception of a hinge leaf.

The door gauge 10 is generally channel-shaped in cross-section and includes a web 14 which has integral therewith and extending rearwardly from one edge thereof a first flange 16. Extending rearwardly from the opposite edge of the web 14 in spaced parallel relation to the first flange 16 is a second flange 18. The flange 18 is removably secured to the web 14 by a pair of suitable fasteners 20.

In order that the door gauge 10 may be removably secured to the door 12, the web 14 is provided with an elongated vertical opening adjacent the flange 18. The opening 22 has disposed therein a front portion of an adjustable plate 26 which has a rear portion of a greater width than the front portion to form shoulders 24 which abut against the rear portion of the web 14 to retain the plate 26 in position. It will also be noted that the front portion of the opening 22 is of a greater width than the rear portion thereof and that the plate 26 is provided with outwardly projecting tabs 28 which prevent the rearward movement of the same.

Referring now to Figure 3 in particular, it will be seen that the opening 22 is of a greater width than the thickness of the plate 26 whereby adjustment of the plate may be accomplished. In order that the plate 26 may be adjusted transversely of the web 14, the flange 18 is provided with an outwardly projecting boss 29 which has an internally threaded bore 30 therethrough. Threadedly engaged in the bore 30 is an elongated fastener 32 whose inner end abuts against the plate 26 and urges the same into clamping engagement with a face of the door 12 adjacent the flange 18. The fastener 32 is provided with a transversely extending pin 34 to facilitate the rotation of the same.

It will be noted that the web 14 is provided with an elongated generally rectangular opening 36 which extends to an edge thereof and communicates with an elongated opening 38 in the flange 16. It will be understood that heights of the openings 36 and 38 are equal to the height of the hinge leaf adapted to be mounted in the door 12 and that the widths of the openings 36 and 38 are equal to the width and thickness of the hinge leaf, respectively. In order to facilitate the engagement of a scriber with a door 12, the upper and lower edges of the opening 36 have outwardly bevelled outer portions 40. It will also be noted that the intersections between the horizontal and vertical portions of the opening 38 terminate in inwardly projecting recesses 42.

Referring now to Figures 5, 6 and 7 in particular, it will be seen that there is illustrated a conventional door jamb construction which is referred to in general by the reference numeral 44. The door jamb construction 44 includes a jamb 46 which has secured to one face thereof a trim strip 48, an edge of the trim strip 48 being offset from the inner face of the jamb 46 to form a recess 50. Secured to the other edge of the jamb 46 is a stop strip 52 which projects inwardly of the jamb 46.

Mounted on the jamb 46 for outlining an area to be cutaway to permit the insertion of a hinge leaf is a jamb guide which is referred to in general by the reference numeral 54. The jamb guide 54 is generally Z-shaped in cross-section and includes a web 56 which has projecting from one edge thereof a first flange 58. Also integral with the web 56 and projecting from an opposite edge of the web 56 in a direction opposite from the flange 58 is a second flange 60.

When the jamb guide 54 is properly positioned on the jamb 46, the flange 58 is seated within the recess 50 and abuts one edge of the jamb 46 while the flange 60 abuts an adjacent edge of the stop strip 52. The jamb gauge 54 is retained in an adjusted position by a pair of conventional fasteners 62, which may be in the form of nails, which are passed through suitable apertures 64 in the web 56 and pass into the jamb 46.

In order that an area of the jamb 46 to be cut-away for the insertion of a hinge leaf may be properly marked, the web 56 is provided with an elongated rectangular opening 66 which extends the full width of the web. The opening 66 also communicates with an opening 68 in the central portion of the flange 58. It will be understood that the heights of the openings 66 and 68 are equal to the height of a hinge leaf to be mounted in the jamb 46 and that the widths of the openings 66 and 68 are equal to the width and depth of such a hinge leaf, respectively. To facilitate the marking of the outline of the portion to be cut-away, the upper and lower portions of the opening 66 are provided with outwardly bevelled outer portions 70.

Referring now to Figures 7 and 8 in particular, it will be seen that there is illustrated a scribe which is referred to in general by the reference numeral 72. The scribe 72 includes an elongated handle 74 which is configurated to conveniently fit one's hand and which has projecting out of one end thereof a generally triangular blade 76. Free edges of the blade 76 are bevelled, the free edges forming a generally V-shaped cutting edge 78.

Referring now to Figure 7 in particular, it will be seen that the scribe 72 is being utilized in scribing the outline of the portion of the jamb 46 which must be removed for the insertion of a hinge. It will be noted that a bottom end 80 of the handle 74 overlies the flange 60 of the jamb gauge 54 and is in abutting relation therewith. It will also be noted that the portion of the blade 76 extending into the jamb 46 is substantially equal to the depth of the recess which must be formed for the reception of a hinge leaf. After the recess is completely outlined in the

jamb 46 or the door 12, the portions of the jamb and door which must be removed may be easily cut out with a chisel.

It will be understood that both the jamb and the door 5 will be conveniently marked at the appropriate places in order that the gauges 10 and 54 may be properly positioned. This may be done by placing the door 12 in its proper position with respect to the jamb construction 46 and simultaneously marking both the jamb 46 and the door 12 with the scribe 72. It will be understood that the scribe 72 is an essential element of the gauge set inasmuch as it is specifically designed for use with the gauges 10 and 54.

From the foregoing, the construction and operation 15 of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claim.

What is claimed as new is as follows:

For use in setting hinges of a door, a door gauge forming an element of a gauge set, said door gauge having a generally channel shaped cross-section including a web and flanges, said web and one of said flanges having openings therein outlining both a face and an edge of a hinge strap, a second opening in said web adjustably receiving a plate, said plate being adapted to clamp a door between the same and said one flange, said second opening being between the first mentioned opening in said web and the other of said flanges, and means operatively connected to said other of said flanges and said plate for urging said plate toward said one of said flanges, said plate being provided with means thereon for retaining the same in position with respect to said gauge, said means comprising a notch at each end of said plate adjacent one side thereof, said notch receiving the edges of the opening in said web.
